UNITED STATES PATENT OFFICE.

HANS PETERSEN, DECEASED, LATE OF DAVENPORT, IOWA; BY STELLA CHARLOTTE PETERSEN, EXECUTRIX, OF DAVENPORT, IOWA, ASSIGNOR TO THE LINOGRAPH COMPANY, OF DAVENPORT, IOWA, A CORPORATION OF MAINE.

TYPOGRAPHICAL MACHINE.

Application filed November 16, 1925. Serial No. 69,553.

This invention relates to improvements in typographical machines and more particularly to an improved cooling system or means for the molds of such machines.

5 The molds of typographical machines, after a short term of use, tend to become overheated so that the castings formed in them no longer maintain their solid and compact character with the sharply defined outlines. 10 that are characteristic of castings which are cast in a properly cooled mold. The castings in an overheated mold tend to become honey-combed, pitted, and spongy with their faces of blurred and imperfect outlines.

15 The object of the present invention is to provide an improved cooling system or means which will maintain the molds properly cooled so that perfect castings may be cast therefrom.

20 A further object of the invention is to provide an improved cooling system for the purpose referred to which can be readily applied to the standard typographical machine equipment without interference with 25 the general form and arrangement of the parts thereof.

The invention comprehends an improved typographical machine mold in which the molding devices or molds proper on the mold wheel have interior channels or cooling fluid courses in the walls thereof and means is provided for conducting a cooling fluid to and from said interior channels or courses. The invention further contemplates an improved cooling system of this kind in which the interior channels or courses of the several molding devices on the mold wheel are connected one with another in series to provide for the circulation 30 of the cooling fluid throughout the interior channels or courses of the several molds from one to another.

35 The invention, with other objects and advantages thereof, and the particular construction, combination and arrangements of parts comprising the same, will be understood from the hereinafter contained detailed description, when considered in connection with the accompanying drawings, 40 forming part hereof and illustrating embodiments of the invention.

In the drawings:

Figure 1 is a front elevation of a mold wheel and molding devices thereon provid-

ed with a cooling system in accordance with 55 the present invention.

Fig. 2 is a transverse section of the mold wheel.

Fig. 3 is a transverse section on the line 3—3 of Fig. 1. 60

Fig. 4 is a section, on an enlarged scale, of the inner part of the mold wheel, the mold wheel axle and its hanger, and associated parts.

Fig. 5 is a detail longitudinal section of 65 one of the molds on the line 5—5 Figure 6.

Fig. 6 is a section of one of the molds on line 6—6 of Figure 7.

Fig. 7 is a detail section on line 7—7 of 70 Figure 6.

Fig. 8 is a section on a dummy mold on line 8—8 of Fig. 10.

Fig. 9 is a section on line 9—9 of Figure 10.

Fig. 10 is a section on line 10—10 of Fig- 75 ure 9.

Fig. 11 is a transverse section on line 11—11 of Figure 3.

Fig. 12 is a transverse section on the line 12—12 of Figure 3. 80

Fig. 13 is a transverse section on the line 13—13 of Figure 3.

Fig. 14 is a front elevation with a dummy mold substituted for one of the regular molds. 85

Fig. 15 is a front elevation of a modified construction in which provision is made for circulating the cooling fluid through the interior channels or courses of one or more of the series of molds. 90

Fig. 16 is a longitudinal section of the modified construction illustrated in Figure 15.

While specific embodiments of the invention are illustrated in the drawings, it will of course be understood that changes and modifications may be made in the particular constructions shown, and the invention may be embodied in other forms, as will appeal to those skilled in the art and falling within the scope of the appended claims, without departing from the spirit of the invention. 95 100

Referring to a detail description of the particular embodiment of the invention illustrated Figures 1 to 13 of the drawings, 1 designates the mold wheel and 2 the axle 105 thereof supported for rotation in the bearing or hanger 3. The axle 2 at the end has a reduced portion 4 upon which the hub of

the mold wheel fits, and the mold wheel is clamped to the axle 2 with an end face thereof tightly fitting against the end face of the axle 2 that adjoins the reduced portion 4 by a nut 5 engaging a threaded part of said reduced portion. The mold wheel 1 is keyed to the axle to rotate therewith by a lug or key 6 on the mold wheel engaging a groove 7 in the reduced portion 4 of the axle. The axle 2 at its other end is provided with an annular shoulder 8, said shoulder and the inner end face of the hub of the mold wheel 1 being properly spaced relatively to the end faces of the bearing or hanger 3 to cooperate therewith to prevent endwise movement of the axle while permitting free rotation of the same. The axle 2 is provided with an opening 9 extending centrally and longitudinally through the same, said opening tapering inwardly from one end of the axle for the greater portion of its length and the remaining portion thereof being cylindrical. Fitting within the opening 9 of the axle 2 is a core member or spindle, said core member or spindle having a tapered part 10 and a cylindrical part 11, the core member or spindle being shaped to correspond with the shape of the opening 9 of the axle 2 to make a rotating fit therewith providing for the rotation of the axle 2 thereabout, said core member or spindle having a shouldered end portion 12 extending beyond the adjacent end of the axle 2 and which is secured by any suitable means (not shown) to the frame or a stationary part of the machine. The other reduced end part 11 of the core member or spindle extends beyond the end of the axle 2, and the core member or spindle is held in position within the opening 9 of the axle 2 by nuts 13 engaging a threaded portion on said reduced end part 11. 14 designates a collar or washer interposed between the shouldered end portion 12 of the core member or spindle and the end of the axle 2, said washer being adapted to rotate upon the core member or spindle and serve to prevent clamping of the axle 2 too tightly to the core member or spindle. The core member or spindle is provided intermediate its ends in the outer face of its tapering part 10 with two annular chambers 15-16 and with interior longitudinally extending channels 17-18 respectively connecting the annular channels 15-16 with ports 19-20, in the shouldered end portion 12 of the core member or spindle. At the ports 19-20, the shouldered end portion 12 of the core member or spindle is provided with threaded openings, as shown, to receive the ends of supply and exhaust pipes 21-22. The axle 2 is provided with interior longitudinally extending channels or ducts 23-24, leading respectively from the annular channels 15-16, in the core member or spindle to

the inner ends of interior radially extending channels 25-26, in the mold wheel 1, said latter channels at their outer extremities communicating respectively with ports 27-28, which extend to the outer face of the mold wheel (see Figures 1 and 2). As will be understood, the annular channels 15-16, and the separate sets of channels 17, 23, 25 and 18, 24 and 26 form conduits for a cooling fluid extending respectively from the supply and exhaust pipes 21 and 22 to the ports 27 and 28 which open to the outer face of the mold wheel.

The mold devices or molds proper on the mold wheel, four of which are shewn in the present instance, are of general standard form, each including a main body part having a front portion 29 and an offset rearwardly extending portion 30, and a cap member 31 secured to the portion 30 by screws 32. The molds are mounted in accordance with the regular practice in openings 33 in the mold wheel 1, the rear offset portion 30 of the molds extending within the opening 33, and the front portion 29 of the mold fitting against and being secured to the front face of the mold wheel by screws 34. Each of the molding devices or molds proper on the mold wheel is provided with an interior course or passageway for a cooling fluid extending completely around the mold cavity, said interior cooling fluid course comprising interior longitudinally extending channels or ducts 35, 36, in the body part 30 and the cap member 31 connected by transverse channels 37, 38, and 39, 40, are channels connecting the ends of the longitudinal channel 35 to ports 41, 42, leading to the rear face of the front portion 29 of the mold. The lower interior longitudinally extending channel 35 of the mold is provided, as shown, intermediate its ends with a constriction 35^a to retard the flow of cooling fluid therethrough and compel the circulation of cooling fluid through the upper longitudinal channel 36, provision being thus made for the circulation of cooling fluid as indicated by the arrows up through the transverse interior channel 37 at one end of the mold through the longitudinally extending channels 35 and 36, from the upper longitudinally extending channel 36 down through the transverse channel 38, through the duct 40 to port 42. Washers 38^a of composition rubber or the like are seated in recesses between the opposing faces of the mold body, liner 31^a and cap 31 to provide watertight joints at the communicating ports. 43, 44, 45 designate interior channels in the mold wheel 1 for connecting the interior cooling fluid courses of certain of the molding devices with each other, said connecting passages each communicating with pairs of ports 43^a-43^b, 44^a-44^b, 45^a-45^b leading to

the front face of the mold wheel and arranged to align with ports 40 and 39, at the adjacent ends of certain of the molding devices. The ports 27 and 28 with which the radially extending channels 25, 26 communicate are arranged, as shown, to align and communicate with the inlet port 41 of one of the molding devices and the outlet port 42 of an adjacent mold, the interior 10 cooling fluid courses of the molding devices being connected in series with the supply and return channels 26, 27, providing for the circulation of the cooling fluid through the interior fluid cooling courses of the several molding devices from one to another.

Cold water or any other suitable cooling fluid may be employed as the cooling medium, this being supplied to the intake pipe 21 under the proper pressure from any 20 convenient source. The water from the supply pipe 21 entering the channel 17 through the inlet 19 passes to the annular chamber 15, and therefrom through the channel 23 and the radially extending channel 25 in 25 the mold wheel to the port 27, and thence through the interior cooling courses of the several molding devices, and returning from the outlet port 42 of the last mold of the series through the port 28 to the radially 30 extending channel 26, the longitudinally extending channel 24, the annular chamber 16, and channel 18 to the exhaust pipe 22, which latter may lead to a receiving tank or waste pipe (not shown).

The interior radially extending channels 25, 26, the interior connecting channels 43, 44, 45, in the mold wheel, and the interior channels 35, 36, 37, 38, 39, and 40 of the molding devices are conveniently provided 40 by drilling intersecting holes as shown, and closing the outer end of the holes by screw plugs 46.

Means is provided whereby if it is not desired to use a complete set of mold devices 45 on the mold wheel, a lesser number of molds may be used while at the same time maintaining the system of circulation of cooling fluid through the interior cooling fluid courses of the remaining molds in series.

The means for this purpose comprises a 50 dummy mold 47, (see particularly Figures 8, 9, 10 and 14), which is adapted to be substituted for one of the regular molding devices, said dummy mold consisting of a

55 substantially rectangular shaped metal block having an interior longitudinally extending channel 48 and ports 49, 50, leading from the ends of said channel to the rear face of the block and adapted to align and communicate with either of the pairs of ports 28—43^a, 43^b—44^a, 44^b—45^a, 45^b—27, which lead inwardly from the outer face of the mold wheel 1. As will be understood one or more dummy mold members 47 may be employed 60 and substituted for one or more of the reg-

ular molding devices on the mold wheel, the dummy mold members 47 being secured to the mold wheel 1 by screws 51, which enter the openings in the mold wheel that are provided for and engaged by the securing 70 screws 34 of the regular molding devices.

In Figures 15, 16, and 17 is illustrated a modified construction that provides for the circulation of the cooling fluid through the interior cooling fluid courses of the 75 molding devices in series, and also for the circulation of the cooling fluid through the interior cooling fluid course of one or more of the molds. This modified construction is the same as that previously described and 80 illustrated in Figures 1 to 12 except that instead of a single supply and return passage 25, 26, 23, 24, leading from the annular chambers of the inner core or spindle through the core and mold wheel, separate 85 supply and return channels in the mold wheel 1 and the core member or spindle are provided for each of the molds, and valves are provided in the system for cutting off the circulation of the cooling fluid from any 90 of the molds. In these views, 52 designates the mold wheel, 53 the wheel axle, 54 the bearing for the axle, and 55 the core or spindle. 56—57, 58—59, 60—61, 62—63, are the separate interior inlet and return 95 passages in the mold wheel for the several molds, and 64—65, 66—67, 68—69, 70—71, are separate interior inlet and outlet channels in the axle connecting the first mentioned sets of passages with the annular chambers 72, 100 73, in the core member 55, 74, 75, 76, and 77 designate rotary plug valves controlling the connecting passages 78, 79, 80 and 81 between the molding devices, and 82 designates similar valves to control each of the separate 105 pairs of inlet and return channels 56—57, 58—59, 60—61, and 62—63.

It will be noted that the special construction and arrangement of parts hereinbefore set forth provides for the circulation of a 110 cooling fluid interiorly of the walls of the mold devices or molds proper completely around the mold cavity. The improved cooling system is of such a character as to be readily applied to standard typographical 115 machine mold equipment, the molding devices or molds proper being of general standard form and interchangeable.

What I claim is:

1. In a typographical machine, molding 120 means including a rotary mold wheel and a mold thereon, said mold being provided with an interior cooling fluid course within the walls thereof, and with an inlet port and an outlet port leading from the exterior of 125 the mold to the interior cooling fluid course, and means connected with said ports for circulating a cooling fluid through the interior course of the mold.

2. In a typographical machine, molding 130

means including a rotary mold wheel and a mold thereon, said mold being provided with an interior cooling fluid course within the walls thereof, extending completely around the mold cavity, and said mold having an inlet port and an outlet port leading from the exterior of the mold to said interior cooling fluid course, and means connected with said ports for circulating a cooling fluid through the interior course of the mold.

3. In a typographical machine, molding means including a mold wheel and a mold thereon, said mold being provided with an interior course for a cooling fluid in the walls thereof, the interior cooling fluid course of the mold including longitudinally extending channels above and below the mold cavity and transverse passages connecting the same, one of said longitudinally extending channels having a constricted portion to retard the flow therethrough and compel circulation through the other longitudinally extending channel, and means providing for circulating a cooling fluid through the interior cooling fluid course of the mold.

4. In a typographical machine, molding means including a rotary mold wheel, a mold, means detachably securing the mold on the mold wheel, said mold having an interior cooling fluid course in the walls thereof and ports leading therefrom to an outer face of the mold which outer face lies against a face of the mold wheel when the mold is mounted thereon, and means provided for a circulation of a cooling fluid through the interior cooling fluid course of the mold including interior conduits in the mold wheel and ports leading therefrom to the outer face of the mold wheel and arranged to align and communicate with the said ports of the mold.

5. In a typographical machine, molding means including a rotary mold wheel, a series of molds, means for detachably securing the series of molds on the mold wheel, each of said molds having an interior course in the walls thereof for cooling fluid and ports leading from said course to an outer face of the mold that lies against a face of the mold wheel when the mold is mounted thereon, and means providing for circulating a cooling fluid through the interior courses of the series of molds, said last mentioned means including interior channels in the mold wheel and ports leading therefrom to a face of the mold wheel arranged to align and communicate with the ports of the several molds.

6. In a typographical machine, molding means including a rotary mold wheel, a series of molds, means for detachably securing the series of molds on the mold wheel, each of said molds having an interior

course in the walls thereof for cooling fluid, and ports leading therefrom to an outer face of the mold that lies against a face of the mold wheel when the mold is mounted thereon, and means providing for circulating cooling fluid through the interior course of the several molds from one to another in series, said last mentioned means including interior channels in the mold wheel and ports leading therefrom to a face of the mold wheel arranged to align and communicate with the ports of the several molds, and a dummy mold device adapted to be substituted for one of the regular molds, means for detachably securing the dummy mold device on the mold wheel, said dummy mold device having an interior channel and ports leading therefrom to an outer face of the dummy mold arranged to align and communicate with the ports in the outer face of the mold wheel similar to the ports of the regular molds.

7. In a typographical machine, molding means including a rotary mold wheel and a series of molds thereon, each of said molds being provided with an interior cooling fluid course in the walls thereof, and means providing for the circulation of cooling fluid through the cooling fluid courses of the molds from one to another in series.

8. In a typographical machine, molding means including a bearing, an axle mounted for rotation in said bearing, a mold wheel fixed on the axle to rotate therewith and clamped thereagainst, and means providing for circulating a cooling fluid in the wall of the mold wheel, said means including interior passages in the wall of the mold wheel, a core member or spindle rotatably fitting within an opening extending centrally and longitudinally through the axle, said core member being provided intermediate its ends in its outer face with two annular chambers, interior longitudinally extending passages leading respectively from said chambers to inlet and outlet ports in the spindle, and with longitudinally extending channels leading from said annular channels to and communicating with the interior passages of the mold wheel.

9. In a typographical casting machine, molding means including a bearing, an axle mounted for rotation in the bearing, a mold wheel fixed on the axle to rotate therewith and clamped thereto, and means providing for circulating a cooling fluid in the walls of the mold wheel, said means including interior passages in the wall of the mold wheel, a core member or spindle rotatably fitting an opening extending centrally and longitudinally through the axle, adjustable means on one end portion of the spindle for holding the same in position in the opening of the axle, said core member having a part tapering inwardly from one end there-

- of and provided intermediate its ends in the outer face of said tapering part with two annular chambers, interior longitudinally extending passages leading respectively from said chambers to inlet and outlet ports in the spindle, and with longitudinally extending channels leading from said annular chambers to and communicating with the interior passages of the mold wheel.
10. In a typographical machine, molding means including a rotary mold wheel and a series of molds thereon, each of said molds being provided with an interior cooling fluid course in the walls thereof, and means
15. providing for circulating cooling fluid through one or more of the cooling fluid courses of the molds.

11. In a typographical machine, molding means including a rotary mold wheel and a mold thereon, said mold being provided with an interior longitudinally extending cooling fluid course within the walls thereof, and with an inlet port at one end, and an outlet port at its other end, said ports leading from the exterior of the mold to said interior cooling fluid course, and means connected with said ports for circulating a cooling fluid through the interior course of the mold.

In testimony whereof I hereunto affix my signature.

STELLA CHARLOTTE PETERSEN,
Executrix of the Last Will and Testament of Hans Petersen, Deceased.
